UNITED STATES PATENT OFFICE.

EDMUND O. SCHWEITZER AND NICHOLAS J. CONRAD, OF CHICAGO, ILLINOIS, ASSIGNEES
TO SCHWEITZER & CONRAD, OF CHICAGO, ILLINOIS, A CORPORATION OF ILLINOIS.

FUSE DEVICE.

1,246,792.

Specification of Letters Patent.

Patented Nov. 13, 1917.

Application filed December 31, 1914. Serial No. 879,829.

To all whom it may concern:

Be it known that we, EDMUND O. SCHWEITZER and NICHOLAS J. CONRAD, citizens of the United States, residing at Chicago, in the county of Cook and State of Illinois, have invented a certain new and useful Improvement in Fuse Devices, of which the following is a full, clear, concise, and exact description, reference being had 10 to the accompanying drawings, forming a part of this specification.

Our invention relates to fuse devices, and especially to fuse devices especially adapted for extra high potentials.

15 An object of the invention is to provide a simple, practical and effective device of this kind and to secure certain highly desirable results such as preventing an arc when the device operates, preventing undue 20 generation of heat at such times, preventing breakage in the device when the fuse blows, and so on.

Other objects of the invention will appear in the further and more detailed consideration 25 of the invention.

In carrying out the invention as herein-after more fully set forth we provide a holder or container for the fuse, such holder or container preferably being of hard relatively unbreakable material, and having a comparatively small bore or channel in which the fuse may be arranged. One end of the fuse is secured to a terminal part of the device, and the other is mechanically 35 connected with a spring which is held normally under restraint by the fuse. When the fuse operates, the spring contracts, separating the end portion or terminal to which the fuse was connected from the other fuse 40 terminal and thereby forming a long gap which will prevent an arc; and owing to the presence of the fuse holder or container an obstacle is in effect interposed in the path of the arc which has a damping or preventive effect thereon, and at the same time 45 the explosion of the fuse is effectively confined so as to prevent damage and other objectionable results. The fuse holder or container, together with the spring is preferably inclosed in a tubular casing which also is desirably provided with arc extinguishing liquid and the spring is desirably combined with a liquid director adapted to direct said arc extinguishing liquid 50 into a space where the fuse explosion has occurred, thereby having another influence

tending to prevent arcing. A removable part forming a vent member is desirably arranged at the end of the tubular casing, so that if necessary said part may become separated from the casing to vent the device, and especially the fuse chamber therein upon operation of the fuse. 60

In the accompanying drawings Figure 1 is a longitudinal section of a portion of a fuse 65 device embodying our present invention;

Fig. 2 is a cross section of the same taken on line 2—2 in Fig. 1;

Figs. 3 and 4 are respectively a longitudinal section and an elevation of a detail 70 of construction;

Fig. 5 is a longitudinal section of a modified form of device;

Fig. 6 is a plan view of the same;

Fig. 7 is a longitudinal section of a fur- 75 ther modification; and

Fig. 8 is a plan view of the same, with a portion thereof broken away for convenience of illustration;

Fig. 9 is a longitudinal section of the up- 80 per end portion of a still further modification; and

Fig. 10 is a cross section taken on line 10—10 in Fig. 9.

Referring first to the device shown in 85 Figs. 1 to 4, inclusive, 1 is a tubular member or casing preferably cylindrical in form and desirably made of some transparent material, such as glass. At the upper end of the member 1 is a sleeve or collar-like member 2 preferably made of metal and encircling the upper end portion of the member 1, but projecting above the upper edge thereof. The bore of the upper member 2 is enlarged as at 3, forming an annular 90 shoulder 4 upon which rests a disk 5, preferably of metal which is loosely mounted so as to be readily removable and so form a vent member for venting the interior of the device. A cap 6 also desirably made of 100 metal is preferably mounted upon the upper end portion of the sleeve 2. A fuse holder or container 7 is arranged at the upper end of the tubular casing 1. While this member 7 might be in various forms or 105 shapes, we preferably make it in the general form of a plug having a body portion adapted to fit loosely in the upper end portion of the tube 1, and also having an annular projection or flange 8 adapted to rest upon the upper edge of the tube 1. This member 7 is provided with a bore or channel 9, in

which one or more fuses 10—10 are extended, said fuses passing substantially through said bore 9. The upper ends of the fuses 10 are secured as by soldering to a terminal 11 conveniently set in a small socket 12 formed in the top of the member 7, a connecting hook or ring 14 being secured to said terminal 11 and extended up therefrom and connected to a metal terminal disk 15 mounted on the top of the member 7, which disk 15 is in turn connected with the metal sleeve or ferrule 2 by means of a flexible conductor 17, whereby said fuses 10 are connected at their upper ends to the metal sleeve or ferrule 2 which is secured to the end flange 18 of a terminal clamp 19, which latter is adapted to be fitted into spring jaws or terminals of some ordinary or well known variety so as to connect the fuse device in circuit.

The lower ends of the fuses 10—10 are secured to a metallic terminal member 20 which extends downwardly and has its lower end threaded at 21 and fitted into a metallic socket piece 22. A cross piece 23 passes through the terminal member 20 and has its ends embedded in the upper portion of a liquid director 24, which latter has a series of inclined side apertures or passages 25—25, and an upwardly tapering passage 26. A spring 27 is confined within the tubular member 1 and has its upper end secured to the socket member 22, whereby said spring normally exerts a downward pull upon said socket member 22 and consequently upon the liquid director 24, and the fuses 10—10. A conductor 28 is also connected with the socket member 22 and extended downwardly within the tube 1, it being understood that the lower end of said socket member is connected with the lower end of the fuse device so that it may be connected to another terminal of the circuit and thereby connect the fuse device as a whole in said circuit. A series of radiator vanes 30 are preferably secured to the metal ferrule or collar 2, said vanes projecting radially outward and affording radiating surfaces. An arc vapor shield 31 conveniently in the form of a metallic plate or disk projecting laterally from the upper portion of the ferrule 2 is desirably provided so as to afford a shield to prevent or stop the movement or development of arc vapor.

Thus it will be seen that in operation when the fuses 10—10 operate by reason of an overload current, the spring 27 will be released and will contract, drawing the liquid director 24 downwardly and so separating the terminal 20 carried thereby from the disk terminal 15, and thereby forming such a long or wide gap as to prevent or break an arc. At the same time the arc extinguishing liquid 33 with which the tube 1 is understood to be preferably filled, such

liquid for example, as carbon tetra-chlorid, will be forced upwardly by the liquid director 24 and injected into the space between the fuse terminals and so offer another influence tending to break or prevent an arc. 70 The fuse container or holding member 7 which may be of bakelite or other suitable material, is in the nature of an obstacle in the path of the arc or at any rate serves to restrict the arc to the small bore or passage 75 9 in said member 7, whereby a repressive and extinguishing influence is exerted upon said arc. At the same time this member 7 serves as a heat insulator to prevent the spread or distribution of heat caused by the 80 blowing of the fuse; and it will be further seen that the member 7 by reason of its substantial and solid plug-like character will limit the explosive action of the fuse or fuses and protect the adjacent parts of the device. 85 The vanes 30—30 tend of course to radiate heat and so prevent undue heating of the device and assist quick cooling of the same after operation. The arc vapor shield 31 serves its useful purpose as above mentioned. 90 The vent member 5 and the member 15 may be lifted bodily by the fuse explosion so as to vent the interior of the tube 1 and member 7 and associated parts, and thereby allow adjustment and equilibrium 95 of pressure and prevent damaging results. The cap 6 may be secured firmly in position in which case the vent member 5 would be blown against the same or said cap 6 may also be loosely mounted so as to permit it 100 to be blown off when the fuse or fuses operate. The vent member 5 is preferably soldered lightly in position so as to hold it against falling or being shaken out of place, but at the same time with insufficient 105 strength to hold it against the operation of the fuse.

Referring to the device shown in Figs. 5 and 6, this device is similar to the one shown in the preceding figures, but this device of 110 Figs. 5 and 6 has two members 7^a and 7^b, in place of a member 7 of the other device. The member 7^a has the bore or passage in which the fuses 10—10 are extended and the member 7^b has a central aperture 35 in 115 which the upper fuse terminal 14^a is confined, said member 7^b being preferably secured to the underside of the vent member 5. The upper fuse terminal 14^a is secured to and held in position by a terminal rod or 120 bar 36 whose upper end is supported by a bridge 37 mounted upon the top of the collar or ferrule 2. We have shown the lower end of the fuses 10 secured to a terminal 38 to which a cross piece 23 is secured, as in the 125 other device, said cross piece having its ends embedded in a liquid director 24^a, which is of suitable form having only the bottom funnel shaped aperture 26 without any side apertures. The upper ends of the spring 27 130

and conductor 28 are secured to the terminal 38 and the tube 1 is preferably provided with carbon tetra-chlorid or similar liquid.

In operation this device is similar to the 5 other device, but in this device the upper member 7^a will be blown out of and away from the rest of the device with the vent disk 5, the bridge 37 being also removable by having its ends soldered to the ferrule 2, 10 so as to be detached therefrom by the explosion of the fuse. The other member 7^a which is more properly the fuse holding or containing member, instead of remaining stationary as in the other device, moves 15 downwardly with the liquid director 24^a and so remains closer to the lower fuse terminal and receives liquid in its longitudinally arranged bore or channel. This emphasizes the arc extinguishing action, because arc extinguishing liquid tends to occupy and completely fill the bore of said member 7^a.

Referring to the device shown in Figs. 7 and 8, this device has member 7 like the member 7 of Fig. 1, but has a bridge 37^a 25 similar to the bridge 37 of Fig. 5. A vent 5 is provided as in both of said preceding figures, and a pin or rod 36 extends down from the bridge 37^a to a fuse terminal member 14^b in a manner similar to the arrangement in Fig. 5. The lower end of the fuse 30 10 is shown connected to a terminal 40 from which a cross piece 23 extends into a liquid director 24^b, which is similar to the liquid director 24 of Fig. 1, but has the members 35 or portions 41 above the side passages 25 projecting laterally beyond the lower portion of the liquid director, as shown at 42, whereby said projecting portions or ends 42 tend to engage the liquid in their downward 40 movement more largely than would be the case if they were flush with the remainder of the liquid director, so that liquid will be more effectively directed into the side openings 25. The device of Fig. 7 is provided 45 with a shield 31 such as shown in Fig. 1. A clip or blade 19 is secured to the ferrule 2 as in Fig. 1, but below this is a metallic collar or sleeve 44 having a threaded connection with the lower end of said ferrule 50 2, the lower end of which sleeve or union 44 encircles the upper portion of another collar or sleeve 45 which surrounds the tubular casing 1, but has a layer 46 of gum or other suitable material interposed between it and 55 the casing 1. Thus a tight connection or joint is made at the upper end of the device.

In the arrangement shown in Figs. 9 and 10 the construction is similar to Figs. 1 and 60 7, but the liquid director 24^c is shown with a much larger bottom opening 26^a and smaller side openings 25^a than in said Fig. 1.

It will be understood that changes and modifications may be made without departing from the spirit of the invention.

What we claim is:

1. In a fuse device, the combination of a tubular containing member, a movable plug-like device at one end of said tubular member, said plug-like device closing off the end 70 of the tubular member, and being provided with a fuse bore or channel, a fuse lying in said bore or channel, a spring in said tubular member engaging one end of said fuse, and means for engaging and supporting the 75 other end of said fuse, said plug-like device being movable outwardly to relieve the pressure generated within the tubular member when the fuse is blown.

2. In a fuse device the combination of a 80 tubular containing member, a movable plug-like device at one end of said tubular member, said plug-like device substantially closing off the end of the tubular member and being provided with an open fuse bore or 85 channel, a fuse in said bore or channel, a spring in said tubular member engaging one end of said fuse, and means for engaging and holding the other end of said fuse, said plug-like device and tubular member being 90 provided with coöperating shoulders for engaging one another to hold the plug-like device in position, said plug-like device being movable outwardly to relieve the pressure generated within the tubular member 95 when the fuse is blown.

3. In a fuse device, the combination of a tubular containing member, a plug-like device at one end of said tubular member, said plug-like device substantially closing off the 100 end of the tubular member and being provided with a fuse bore or channel, a fuse, an end of which is disposed in said bore or channel, a spring in said tubular member engaging one end of said fuse, and means for 105 engaging the other end of said fuse to support the same, said plug-like device being provided with an annular shoulder adapted to engage the end of said tubular member, said plug-like device being movable outwardly to relieve the pressure generated 110 within the tubular member when the fuse is blown.

4. In a fuse device the combination of a 115 tubular member, a plug-like device at one end of said tubular member, said plug-like device being provided with a fuse bore or channel, a fuse in said bore or channel, a spring in said tubular member engaging one end of said fuse, means for engaging the 120 other end of said fuse, and a liquid director having central and side orifices, said director being smaller than the bore of the tubular member so as to permit the entry of liquid into said side orifices.

5. In a fuse device, the combination of a 125 tubular member, a plug-like device at one end of said tubular member, said fuse device being provided with a fuse member, and said plug-like device having a bore or channel 130

- affording an outlet passage from the interior of said tubular member, a spring in said tubular member engaging one end of said fuse, means for engaging the other end of said 5 fuse, and a vent member mounted at the outer end of said plug-like device opposite said bore or channel, said vent member having a connection permitting its removal on the operation of the fuse.
10. 6. In a fuse device, a tubular casing, a plug supported at the end of said casing and substantially closing off said casing, said plug having an open bore therethrough, a non-fusible terminal member at one end of 15 said bore, said terminal member being larger than said bore and resting against the top of the plug, a fuse secured to said terminal member, and a spring normally under tension connected to the fuse at the other side 20 of the plug, said spring tending to pull said terminal member against the plug.
7. The combination with a fuse, of a holder or container for said fuse comprising a member of relatively hard material provided with a bore or passage for the fuse but appreciably larger than the fuse, means at one end of said bore or passage for drawing upon said fuse, means at the other end of said bore or passage for engaging said 25 fuse to hold it under strain by said drawing means, a venting member mounted adjacent the end of said fuse which is engaged and held in restraint, and a liquid director having an opening or passage for the direction 30 of liquid, said liquid director being attached to said fuse adjacent to said spring, and a casing containing said liquid director, and also containing arc extinguishing liquid.
8. In a fuse device, the combination with 35 a fuse of a liquid director having a central passage and also having side passages for the direction of liquid to prevent the formation of an arc.
9. In a fuse device a liquid director having a central bore or passage tapering at one end and also having side bores or passages opening into said central bore or passage and having an inclination similar to the 40 tapering end of said central bore or passage.
50. 10. A fuse device comprising a tubular member having one end provided with a movable closure containing a fuse, a spring within said tubular member acting upon the adjacent end of said fuse, and a removable 55 covering member covering the outer end portion of said closure, said covering being adapted to be removed by blowing of the fuse.
11. A fuse device comprising in combination, a tubular casing, a plug member serving as a closure for one end of said casing and having a longitudinally extending bore or channel containing a fuse, a spring with- 60
- in said tubular casing engaging and acting upon the inner end of said fuse, a metal ferrule encircling the end portion of said tubular casing containing said plug member, said metal ferrule projecting beyond the end of said plug member, and a disk mounted removably for venting purposes 70 upon the projecting end of said ferrule.
12. A fuse device comprising in combination, a tubular casing, a plug member serving as a closure for one end of said casing and having a longitudinally extending bore 75 or channel containing a fuse, a spring within said tubular casing engaging and acting upon the inner end of said fuse, a metal ferrule encircling the end portion of said tubular casing containing said plug member, said metal ferrule projecting beyond the end of said plug, a disk mounted removably for venting purposes upon the projecting end of said ferrule, and a cap member mounted upon and covering the projecting end of said ferrule.
13. A fuse device comprising in combination, a tubular casing, a plug member serving as a closure for one end of said casing and having a longitudinally extending bore 80 or channel containing a fuse, a spring within said tubular casing engaging and acting upon the inner end of said fuse, a metal ferrule encircling the end portion of said tubular casing containing said plug member, said metal ferrule projecting beyond the end of said plug member, and a disk mounted removably for venting purposes upon the projecting end of said ferrule, said projecting end of said ferrule having the 85 end portion of its bore enlarged and said venting disk being fitted into said enlarged portion of said bore.
14. A fuse device comprising in combination, a tubular casing having one end provided with a plug which serves as a closure and contains a fuse, a metal ferrule surrounding the end of said casing containing said plug and also surrounding an end portion of said plug which projects from said 90 casing, a sleeve rigidly connected with said casing below said metal ferrule and a second sleeve mounted upon and outside of the lower end of said metal ferrule and the upper end of said first mentioned sleeve, 95 said second mentioned sleeve having threaded connection with said members.
